(57) **CLAIM**

The ornamental design for a cable as shown and described.

DESCRIPTION

FIG. 1 is a perspective view of a cable showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the cable that form no part of the claimed design. The cable is shown with symbolic breaks in its length and the appearance of any portion of the cable between the break lines form no part of the claimed design.
